UNITED STATES PATENT OFFICE.

CHARLES V. STRICKLAND, OF WINSTON-SALEM, NORTH CAROLINA, ASSIGNOR TO R. J. REYNOLDS TOBACCO COMPANY, OF WINSTON-SALEM, NORTH CAROLINA, A CORPORATION OF NEW JERSEY.

PINTLE-INSERTING MACHINE.

1,413,627.

Specification of Letters Patent. Patented Apr. 25, 1922.

Application filed July 29, 1919. Serial No. 314,013.

To all whom it may concern:

Be it known that I, CHARLES V. STRICKLAND, a citizen of the United States, residing at Winston-Salem, in the county of 5 Forsyth and State of North Carolina, have invented new and useful Improvements in Pintle-Inserting Machines, of which the following is a specification.

This invention relates to hinge forming 10 machines, and particularly to a machine for attaching hinge pintles to sheet metal blanks. In particular, it involves various improvements in such machines of the type shown in the United States Patent to Rich- 15 ter No. 1,096,863, issued May 19, 1914; though the improvements are mainly applicable also to other types of machine.

Machines of this general nature handle a 20 sheet metal blank, which may either be flat or formed into any other shape, the preferred type operating on flat blanks. The blanks are provided with suitable projecting elements, which the machine wraps about a wire pintle automatically cut off and 25 brought into engagement with the blank elements. By this operation the pintle is permanently mounted on the blank with spaces 30 between the blank elements where the pintle may be engaged by the similar elements of the other hinge member.

An important feature of these machines 35 is the accurate control of the wire feeding mechanism, so that a proper length of wire may be located accurately and without any deformations therein in juxtaposition to the blank elements or tongues with engage the pintle.

A principal feature of my invention is the 40 provision of improved wire feeding means, together with a more efficient control therefor.

A further object is the employment of such 45 means which will maintain positive control of the wire, and which may be adjusted to regulate with the greatest accuracy the amount of wire fed forward.

I have also devised mechanism of this type 50 which is capable of automatic control through the presence or absence of blanks in proper position to receive a pintle, so that no wire will be fed to the pintle cutting mechanism when there is no blank positioned to receive a pintle. The specific object of this feature is to provide wire feeding

mechanism which is normally maintained, 55 as by resilient pressure, in operative position, and is rendered inactive only upon failure to feed a blank to its proper station.

In the specific embodiment of my invention, I employ a machine adapted to operate 60 upon flat metal container body blanks, which after receiving the pintle are bent into shape to form the container body, the machine for performing the latter operation including a guideway along which the blanks are fed. 65 I have reconstructed and altered the arrangement and mechanism of the machine so that it may be mounted directly upon the body forming machine, and is adapted to feed the pintle blanks directly to the guideway of the latter. In this arrangement I have also provided a drive connection between the driving mechanism of the body machine and that of the pintle machine, to assure complete accuracy and coordination 70 between the two. Moreover, I have provided means, also coordinately driven, for accurately registering the blanks on the guideway of the body forming machine.

Another feature of my invention is the 80 improvement of the feed channel, which may be employed for intermittently advancing the blank successively to the pintling mechanism. With blanks of the type usually employed, which are lithographed on one 85 side, it is not only important to have them fed positively and positioned with complete accuracy, but also to accomplish these objects without in any way marring the lithographed surface. To this end I have improved the feeding arrangement to produce a minimum of friction on the lithographed 90 surface, and have provided means for pintling most economically and effectively for the relatively rapid wear of the sides of the 95 channel caused by the constant friction of the sharp blank edges with a limited area on said sides.

Further objects and advantages will be apparent from the following description 100 taken in connection with the accompanying drawings in which:

Figure 1 is a front view of the entire machine mounted on a body forming machine, part being broken away,

105 Figure 2 is a front view on a larger scale of the chief operating mechanism of my machine, parts being broken away,

Figure 3 is a top plan view of the blank and wire feeding mechanism,

Figure 4 is a sectional view on line 4—4 of Figure 2,

5 Figure 5 is a sectional top view of the wire straightening and feeding mechanism taken just above the feeding rolls,

10 Figures 6, 7, and 8 are vertical sectional views through the clinching head and the feed, showing the successive steps in inserting and clinching the pintle,

15 Figure 9 is a fragmentary plan view of the lower die co-operating with the clinching head,

15 Figure 10 is a cross sectional view through the feed taken on line 10—10 of Figure 2,

Figure 11 is a plan view of the body blank with the pintle recess cut out,

20 Figure 12 is a fragmentary view of the blank, showing the first step in inserting the pintle,

Figure 13 is a sectional view on line 13—13 of Figure 12,

25 Figure 14 is a fragmentary view similar to Figure 12, showing the pintle in final clinched position,

Figure 15 is a sectional view on line 15—15 of Figure 14, and

30 Figure 16 is a sectional view on line 16—16 of Figure 14.

The machine is adapted to receive rectangular decorated blanks at one end of a feed channel or guideway, where the blank is picked up and fed by successive steps first to the cutting mechanism and then to the clinching head. This feed channel, shown best in Figures 1 and 10, has a flat bottom which may consist of a pair of bottom plates 20 and 21, mounted on a support 35 which may be of any desired form. I have shown the feed channel carried mainly by bracket 22 mounted on frame 23 of a body forming machine which also carries one end of the channel. The upper faces of plates 40 20 and 21 form a flat channel 24 along which body blanks 25 are slid. At opposite sides of the channel are upstanding flanges 26 and 27, preferably formed integral with the outer edges of plates 20 and 21 respectively. These 45 flanges may form edge guides for the blank, but I prefer to mount detachable guides thereon, as this portion of the channel is subject to constant friction from the edges of the blanks, and consequently is the first 50 to wear out. I may provide various forms of edge guides. In the construction shown, I detachably mount a strip 28, preferably composed of hardened steel, on the inner surface of flange 27 as by screws 29. On 55 the inner face of the opposite flange 26, I mount a similar strip of hardened steel 30 as by screw studs 31, on which the strip is slidably mounted, spaced from the inner face of flange 26. Between strip 30 and 60 65 the adjacent flange 26 are located a plurality

of spring elements, preferably in the form of short bowed springs 32 through which studs 31 pass. The strip 30 is thus held in resilient, adjustable contact with the edge of the blank 25, and holds it firmly in position in the channel without causing it to bind. It will be apparent that, in the construction shown, four wearing surfaces on each strip can be presented to the edge of the body blank, as the strips are reversible, 70 both as to top and to bottom, and as to front and rear faces, since screws 29 and studs 31 are equidistant from the top and bottom of the strips and are equally spaced 75 apart.

80 I have provided means for sliding body blanks along channel 24 by a step by step movement. This may consist of a feed bar 33, slidably mounted between plates 20 and 21, preferably having its upper face flush with, and forming part of the bottom of channel 24. Feed bar 33 is pivotally connected through lugs 34 to link 35 pivoted at its opposite end to the upper end of rock arm 36 which is pivoted at its lower end to bracket 22 and connected intermediate its ends to connecting rod 37 which carries an eccentric strap 38 engaging an eccentric 85 39 on vertical shaft 40, carried by the frame of the machine and preferably driven 90 through bevel gears 41 from drive shaft 42 of the body forming machine. Connecting rod 37 is attached at its ends to eccentric strap 38 and to the pivot member on rock arm 36 by oppositely threaded connections, 95 so that the normal distance of the rock arm 36 from the eccentric may be adjusted by rotating rod 37. As will be seen, this will vary the location of the blanks at the end of the feeding stroke of the feed bar and facilitates the accurate positioning of the blanks 100 in register with the operating mechanisms. It is apparent that various other arrangements may be made for reciprocating the feed bar, independently of the body forming 105 machine drive. While any method of supplying the blanks to the feed mechanism may be used, my machine is adapted for hand feeding, to facilitate which I have located a platform 42 at the rear of the 110 left hand end of the channel, upon which may be piled the rectangular blanks ready for feeding.

115 I have provided means on feed bar 33 for engaging the rear edges of successive blanks. In the form shown, I have provided a series of identical engaging elements spaced along the feed bar by a distance slightly greater than the length of a blank. Each of these 120 elements, shown best in Figure 2, may consist of a dog 43, pivoted at 44 in an undercut recess in the feed bar 33, its inner end 45 being normally pressed downward into contact with the bottom of the recess, by a spring 46. In its normal position, the 125 130

outer end of the dog projects slightly above the upper surface of the feed bar into the channel, and is adapted to engage the rear end of a blank.

5 I also provide means for holding the blanks in position against the bottom of the channel. This means preferably consists of a plurality of blocks 47, shown best in Figures 2, 3, and 10. These blocks may be of 10 wood or other suitable material, their weight being sufficient to hold the blank against the channel bottom without marring the decorated surface of the blank during the feeding thereof along the channel. Blocks 47 15 are arranged to rest lengthwise on the bottom of the channel, and are loosely held in position by guide plates 48 projecting over the top of flange 26 and adapted to ride on guide pins 49, carried by the flange. Any 20 desired number of blocks 47 may be used, but they form, in any event, a substantially continuous pressure element bearing on the upper surface of the blank. The pressure from blocks 47 and strip 30 on the blanks 25 is sufficient to hold them in place when the feed bar 33 is traveling toward the left after completing a feed stroke, dogs 43 sliding under blanks 25, springs 46 being relatively weak. The feed operation consists of a forward or feeding motion of the feed bar in 30 which each dog 43 carries a blank forward along the channel for a fixed distance, and a return motion of the feed bar, in which each dog is pulled back under the preceding 35 blank until it engages the rear edge thereof, when the forward motion is again started. The operations hereinafter described are performed on the blank during the back-work stroke of the feed bar, the operating 40 mechanisms serving further to hold the blanks in position.

The main operating mechanism is mounted on a ram 50 reciprocated vertically in guideways carried by overhanging arm 51 45 through connecting rod 52 carried by crank 53 on shaft 54 mounted at one end on bearings 55 in arm 51, and at the other end in a bearing 56, which may be carried by the body of the machine. Shaft 54 is driven by 50 means of bevel gears 57 from shaft 40 and preferably is constructed in two parts detachably connected, as by collar 58 keyed to both parts of the shaft 54, to facilitate assembly and repair of the machine. It will 55 be apparent that the operative mechanism may be reciprocated in other ways, if desired. Mounted on the lower end of ram 50 is the carrier head, consisting of a horizontal plate 59, shown best in Figures 2 and 6. 60 I mount on plate 59 the cutting head and the crimping head, in any desired way. I have shown a downwardly extending flange 60 at the rear of head 59 near its left hand end, to which the cutter 61 is detachably 65 fixed as by screw 62. The face of the cutter

is so shaped that it will cut the far edge of the blank to form a pintle engaging element. This element preferably is produced by cutting a series of spaced recesses 63 in the blank, leaving projecting tongues 64 70 between them, as shown. I have shown the form of hinge which has two tongues on the body blank, but obviously any number may be used. Mounted in plate 20 or, if desired, formed as a part thereof, is the die cooperating 75 with the cutter.

At the opposite end of the rear edge of carrier head 59 is a similar downwardly projecting flange 63^a, having at each end short forwardly projecting end flanges 64^a. A 80 plate 65 is detachably mounted across the front ends of flanges 64^a to define a guideway between flanges 63^a and 64^a and said plate, in which the presser block 66 is adapted to reciprocate vertically. This block is 85 normally held in depressed position against lugs or other stop means, preferably engaging plate 65, by means of a spring element of any desired form engaging the upper face of the block. I have shown a block rubber 90 spring 67 mounted on standards 68 on the upper side of plate 59, the lower end of the spring carrying a plate 69, slidable vertically on said standards and carrying plungers 70, passing through plate 59 and bearing 95 yieldably against the upper side of head 66.

The pintle inserting mechanism is designed to perform the entire operation of crimping the pintle in place during a single 100 downward motion of the mechanism. To accomplish this object, the pintle is first pressed into the tongues 64, forcing them down into a recess 71 in crimping die 72, which is either mounted in or forms an 105 integral part of plate 21. Recess 71 is shaped in such a way that when the pintle is pressed against the tongues 64 and adjacent portions of the blank, the recess accommodates the downwardly bent portions to form a 110 sunken seat for the pintle. I also provide means for simultaneously turning the outer ends of the tongues upwardly, preferably to a position at right angles with the blank body. This means preferably consists of a 115 fixed lip 71^a which, in the construction shown, forms the rear edge of depression 71; but it will be apparent that other fixed abutments or other members may be used instead of lip 71^a to turn the outer ends of 120 the tongues upwardly either by being fixed in such a location or being movable against the tongue ends to force them upward. In the construction shown, it will be noted that lip 71^a practically forms an element separate 125 from the depression in front of it, having the independent function of turning the tongue ends upward while the depression receives the blank to form a pintle seat. These upwardly directed ends are then bent 130

around the pintle to firmly hold it in place. Presser block 66 is operated to press the pintle into the holding tongues to form a seat for the pintle. For this purpose, the block has a flat lower face 73 lying above recess 71. At the inner edge of face 73 are located a plurality of downwardly projecting fingers 74, registering with recesses 75 in die 72, leaving tables 76 between the recesses, the blank being so positioned that tongues 64 are located opposite and rest on tables 76. Spaced outwardly from and opposite to each finger 74 is a guide rod 77, slidably mounted in a bore 78 in head 66, a spring 79 located in the bore resiliently pressing the guide rods downward.

I mount the tongue clinching mechanism on the carrier head. This may consist of clinching fingers 80 pivoted in vertical recesses in the lower edge of flange 63, each finger being located above one of the tables 76. A spring pressed plunger 81 bears against the forward end of the extended upper face of each finger, normally holding its lower incurved end 82 in its rearmost position. Head 66 is recessed opposite the lower end of each finger 80 to permit the finger to swing forward between fingers 74. As will be seen from Figures 6, 7, and 8, the pintle is inserted lengthwise between guide rods 73 and fingers 74, being prevented from sliding out of registry with recess 71 by the guide rods and fingers. The descent of the carrier head brings the lower face 73 of the presser block against the pintle and presses it into tongues 64, curving their outer ends upwardly, as shown in Figure 7. Face 73 then comes into contact with the surface of the blank, the motion of the head 66 stops, the continued descent of the carrier head forces flange 63 downward against the resistance of spring 67, head 66 riding up in its guideway. The lower end 82 of each clinching finger 80 comes into contact with a table 76 and the further descent of the flange 63 causes the finger end to slide forward and clinch the upturned ends of tongues 64 over the depressed pintle. It will be noted that presser block 66 is extended beyond the end recesses 63 and presses the pintle into the blank at each side of said end recesses, into the position shown plainly in Figure 16, so that the pintle is seated at its ends in depressions in the blank body.

The pintle may be fed to the machine in any desired way. I have shown a preferred form which includes means for intermittently feeding a wire and cutting off the proper length therefrom, the device also being adapted for straightening the wire while it is being fed. The wire feeding mechanism, best shown in Figures 2 and 3, is mounted on a bracket 83 attached to overhanging arm 51. On the outer end of the

bracket are two parallel vertical shafts 84 and 85, mounted in upper bearings 86 and lower bearings 87 and 88 in the bracket. The shafts are connected above the upper bearings 86 by meshing pinions 89, so that they revolve in opposite directions. The rear shaft carries intermediate its upper and lower bearings a ratchet 90 engaged by pawl 91, mounted on rock arm 92, pivoted loosely on shaft 84. Link 93 is adjustably pivoted, by means of pivot bolt 94 mounted in slot 95, on the outer end of rock arm 92 and carries on its opposite end, as shown in Figure 1, eccentric strap 96 engaging eccentric 97 mounted on vertical shaft 40. It will be seen that the rotation of shaft 40 will operate the rock arm 92 and intermittently revolve shafts 84 and 85. The adjustment of bolt 94 in slot 95 will vary the extent of swing of rock arm 92, thus varying the degree of rotation of shafts 84 and 85 and regulating the amount of feed, as will be hereinafter seen. Check pawl 98 is mounted on a lug 99 attached to bracket 83 to prevent reverse motion of the ratchet.

On the lower end of shaft 84 is mounted feed roller 100, pressed against and cooperating with roller 101 similarly mounted on the lower end of shaft 85 to feed the pintle wire, which passes between them. These rollers are grooved to straighten any small irregularities in the wire, and are pressed together with sufficient force to grip the wire and feed it. This pressure may be adjustably obtained by having bearing 88 of the shaft 85 carried by a block 102, which is mounted in ways in bracket 83 and normally pressed toward shaft 84 by a bolt 103, threaded in a detachable plate 104 mounted on the lower face of the bracket, said bolt 103 bearing against the outer face of block 102. It will be apparent that, if desired, spring pressed means may be used, pressing against block 102 and may be adjustable by mounting it with its outer end in contact with bolt 103, as shown in Figure 4. The upper bearing 86 of shaft 85 is sufficiently loose to permit the slight play necessary in adjusting the position of block 102 to produce the proper pressure between the feed wheels; or, if desired, an adjustable bearing similar to the lower bearing may be inserted instead of the fixed bearing 86 for shaft 85. In order to straighten the pintle wire before delivering it to the pintle inserting mechanism, I have provided a straightening wheel 105 adjustably mounted on an extension of bracket 83, and grooved so that the wire passes partly around wheel 105 and then a short distance 125 in the opposite direction around roller 100 to the point of contact with roller 101. This will serve to iron out irregularities in the wire. Guide slot 106, through which the wire passes from a holder outside the ma-

chine, is carried by lug 107 attached to the bracket extension upon which wheel 105 is mounted. Upon the opposite side of rollers 100 and 101 from lug 107 is mounted a 5 grooved guide roller 107^a adjustably fixed on the lower side of bracket 83, the axis of roller 107^a being adjustably clamped in a transverse slot in the bracket. The pintle wire is fed to the clinching mechanism 10 through a passage in guide block 108, which fits closely against the side of the reciprocating presser block 66 so that the edge of the block, in its descent, will shear off the wire. The parts are so proportioned that 15 this will not occur until guide rods 77 are in contact with the face of the blank and fingers 74 are slightly below the face so that the wire is positively located above recess 71. The feeding operation of the wire is 20 so timed that the wire is fed forward under head 66 during the upward motion of the head, and is held stationary while the head is descending, rock arm 92 being on its back stroke during the pintle cutting and 25 clinching operation.

I have further provided means for preventing the wire feed from operating when no body blank is located under the presser block. To accomplish this object, I provide

30 a relatively heavy arm 109 pivoted at one end to an upstanding extension 110 on the rear channel flange 27. The other end of arm 109 has a rearwardly extending stud 111 to which is connected, by means of link 112, a lever 113 pivoted at 114 to bracket 83, the opposite end of the lever projecting through the bracket and being formed into an arcuate releasing cam 115, having a bevelled upper face 116. A pin 117 mounted 35 on pawl 91, extends to a point immediately above face 116 of the releasing cam. The free end of arm 109 is positioned so as to rest on the upper surface of a blank located in position beneath the presser block. When 40 no blank is so located, the end of arm 109 drops into a recess 118 in plate 21, shown in Figures 2 and 10, thus pulling the left hand end of lever 113 downwardly and elevating releasing cam 115, pin 117 being 45 pushed outwardly by the inclined face 116 of the cam, leaving pawl 91 out of engagement with ratchet 90. In this position, it will be apparent that arm 92 may rock back and forth continuously without rotat- 50 ing shafts 84 and 85 to feed the wire, as the lower end of pin 117 slides back and forth along face 116 of the releasing cam and holds pawl 91 out of engagement, regardless of the position of arm 92. Con- 55sequently no wire is fed in the absence of a body blank under the crimping head.

As stated, the blank feeding mechanism is so constructed as to be adapted for feeding the pintled blanks to the feedway of a stand- 60 ard body forming machine. I have provided

mechanism adapted to be mounted on the latter to receive the blanks delivered from the feed of my machine and position them accurately on the body machine feed so that the carriage of the latter will engage them 70 without any manipulation by the operator. This mechanism preferably consists of a lever 119 pivoted on a bracket 120 mounted on the bed of a body forming machine, one end of the lever carrying a roller 121 engaging 75 cam slot 122 in cam 123 mounted on shaft 40. The opposite end of lever 119 carries positioning plate 124, mounted adjacent to the end of the pintle machine feed and shaped to guide and hold the pintled blank 80 in position on the feedway of the body machine. Cam slot 122 is so shaped and synchronized with the feed of the blanks, both being driven from shaft 40, that positioning plate 124 is lifted during the feeding motion 85 of the pintle machine to receive a blank, and descends during the return motion of the feeding mechanism, locating the blank properly so that it is engaged and removed by the carriage of the body machine prior to the 90 feeding of the next succeeding blank. This mechanism, of course, will be omitted when my machine is operated as a separate unit.

The operation of my machine is as follows: The decorated rectangular blanks are 95 fed in any desired manner, by hand or otherwise, onto the left hand end of channel 24, which is left uncovered by block 47 for this purpose. The first of the dogs 43 engages its edge and during the forward motion of feed 100 bar 33, the blank is advanced one step into position under the first block 47. The feed bar is then retracted and another blank is inserted. On the next forward motion, both blanks are advanced. In this or a subsequent 105 advancing step, the blank is positioned under cutter 61, which descends during the return motion of the feed bar and cuts the edge of the blank in a suitable location so as to form a pintle engaging element, which 110 may consist of a succession of tongues and recesses. Ram 50 then rises and the cut blank is advanced one step to position it beneath the clinching mechanism, arm 109 riding over the upper surface of the blank and 115 maintaining the wire feeding mechanism in operative position. Through eccentric 97 the rock arm 92 is actuated to revolve shafts 84 and 85 and feed a suitable length of wire through guide block 108. During the return 120 motion of the feed bar, the carrier head descends, first cutting off the pintle, then pressing it into the blank to form a seat, upturning the ends of the tongues, and finally clinching the tongues about the pintle. Upon 125 the ascent of the carrier head, the next blank, which has just been recessed, takes its place. Each blank is fed to the delivering end of the channel, where it is projected onto the feed guideway of the body forming machine, 130

the receiving plate 124 being lifted while the forward motion of the feed bar inserts a pintle blank on the guideway, and being dropped to engage the blank and position it 5 while the feed bar is on its back stroke.

If my machine is operated as a separate unit, any desired form of receiver for the pintled blanks may be provided.

For purposes of illustration, I have shown 10 my pintle inserting mechanism as applied to a special form of machine for producing a can body, but it will be apparent that the pintle attaching mechanism may be utilized to attach a pintle to various forms of metal 15 articles, and its scope is not confined to the specific use herein shown.

While I have described a specific form of blank, a specific form of pintle supply including a wire feed, and specific cutting and 20 pintle inserting mechanisms, it will be apparent that numerous changes in details of the mechanism may be made; and I do not consider my invention to be limited to the specific form disclosed, further than is necessary 25 situated by the scope thereof as covered by the claims.

I claim:

1. In a pintle inserting machine, means for advancing a continuous wire from which 30 successive pintles may be cut, including a wire engaging roller, means for rotating said roller to feed the wire, and a device for normally maintaining said rotating means in inoperative position, said device being 35 rendered inactive by the presence of a blank in pintle inserting position.

2. In a pintle inserting machine, means for advancing a continuous wire from which successive pintles may be cut, including a 40 wire engaging roller, means for rotating said roller to feed the wire including a reciprocating pawl, and a device for normally rendering the rotating means inoperative by retaining the pawl in inactive position, said 45 device being rendered inactive by the presence of a blank in pintle inserting position.

3. In a pintle inserting machine, a horizontal feedway for blanks, pintle inserting mechanism operating on blanks in said feedway, and wire feeding mechanism for supplying pintle wire to the inserting mechanism, including horizontal rollers engaging the wire, one of said rollers having a vertical shaft, means for intermittently rotating 50 said shaft, means for feeding blanks along the feedway, and a common drive system for synchronizing the feed of said blanks and pintle wire.

4. In a pintle inserting machine, a horizontal feedway for blanks, pintle inserting mechanism operating on blanks in said feedway, and wire feeding mechanism for supplying pintle wire to the inserting mechanism, including horizontal rollers engaging 60 the wire, one of said rollers having a vertical 65

shaft, means for intermittently rotating said shaft, means for feeding blanks along the feedway, and a device for normally rendering the shaft rotating means inoperative, said device being rendered inactive by the 70 presence of a blank in pintle inserting position.

5. In a pintle inserting machine, wire feeding mechanism including a pair of opposed wire gripping rollers, and a wire 75 straightening roller engaging the wire at a point offset from the line of passage of the wire between said gripping rollers.

6. In a pintle inserting machine, wire 80 feeding mechanism including a pair of opposed wire gripping rollers, a wire straightening roller engaging the wire at a point offset from the line of passage of the wire between said gripping rollers, and a guide for directing the wire to the straightening 85 roller at an angle to its line of departure therefrom.

7. In a pintle inserting machine, wire 90 feeding mechanism including a pair of opposed wire gripping rollers, wire straightening means including a device for guiding the wire about a substantial portion of the periphery of one roller before passing between the rollers; and a straightening guide 95 engaging the wire beyond the gripping rollers on the concaved side of the wire.

8. In a pintle inserting machine having an inserting station, means for advancing a continuous wire, including a pair of rotatable elements between which the wire is 100 clamped, and means for rotating said elements; means for advancing successive blanks to the inserting station, means rendered inoperative by the presence of a blank in the inserting station, for rendering said 105 rotating means inoperative and preventing thereby the advance of the wire, and means for severing a pintle length from the end of the wire and attaching it to the blank.

9. In a pintle inserting machine having an inserting station, means for advancing a continuous wire, including a pair of rotatable elements between which the wire is clamped, and means for rotating said elements, including a ratchet and an oscillating pawl engaging said ratchet; means for advancing successive blanks to the inserting station, means rendered inoperative by the presence of a blank in the inserting station, for rendering said rotating means inoperative by holding the pawl out of engagement with the ratchet, and preventing thereby the advance of the wire, and means for severing a pintle length from the end of the wire and attaching it to the blank.

10. In a pintle inserting machine having an inserting station, means for advancing a continuous wire, including rotating elements between which the wire is clamped, and means for intermittently rotating one of said 130

elements, said last means including a ratchet and a pawl normally maintained in engagement with the ratchet, a cam element adapted to force said pawl out of engagement with

5 the ratchet, a member shifted from normal position by the insertion of a blank in the inserting station, and means connecting said last named member with the cam member adapted to move the cam member out of engagement with the pawl and permit the latter to engage the ratchet when a blank is positioned in the inserting station.

11. In a pintle inserting machine having an inserting station, means for feeding successive blanks to said station, means for intermittently advancing a continuous wire the length of a pintle, including a pair of rotatable members between which the wire is clamped, driving connections between said 20 members, a ratchet operatively connected to one of said members, an oscillating arm mounted coaxially with said ratchet, means for oscillating said arm, a pawl carried by the arm normally maintained in engagement 25 with the ratchet, an arm shiftable relative to the ratchet, a cam carried by said arm having a face lying adjacent to the normal path of the pawl and adapted to force the pawl out of engagement with the ratchet without interfering with its oscillation, and means for maintaining said cam in position to hold the pawl away from the ratchet, said last named 30 means being rendered inoperative by the presence of a blank in the inserting station.

35 12. In a machine of the class described, pintle engaging mechanism, blank feeding means for positioning a blank in said mechanism to receive a pintle, means for feeding a pintle to the pintle engaging means, said feed means including a ratchet and a pawl engaging the ratchet, continuously operated to actuate the pintle feed means, a disconnecting element adapted to engage the pawl and hold it out of engagement with the 40 ratchet, permitting the continuous actuation of the pawl but preventing any movement of the feed means thereby, and a member connected to the disconnecting element and normally resting in the path of the blanks, the 45 construction being such that the member is shifted by the feeding of a blank to the pintle engaging mechanism and operates to shift, in turn, the disconnecting element and permit the pawl to engage the ratchet, thus operating the pintle feed in the presence of a blank, but rendering it inoperative in the absence 50 of a blank.

55 13. In a machine of the class described, a guideway adapted to slidably receive a plurality of blanks, in frictional contact with one wall thereof, and a removable friction

plate mounted thereon adapted to be reversed so as to present a new friction surface for the action of the blanks.

14. In a machine of the class described, a 65 guideway for slidably receiving a plurality of blanks, a wall resiliently pressed against the blanks to force them into contact with the opposite wall, said resiliently pressed wall being reversible to present a new friction 70 surface to the blanks.

15. In a machine of the class described, a guideway for slidably receiving a plurality of blanks, resilient means on one side of the guideway for pressing the blanks into contact with the opposite wall, and a plate detachably mounted on said opposite wall so constructed as to be reversible to present a new frictional surface to the sliding blanks. 75

16. In a machine of the class described, a 80 guideway for slidably receiving a plurality of blanks, and a member resting by gravity upon the blanks to hold them in contact with the bottom of the guideway.

17. In a machine of the class described, a 85 guideway adapted to slidably receive a plurality of blanks, a reciprocating feed member adapted to slide the blanks along the guideway during the feed motion of the member, and means for holding the blanks 90 in fixed position during the return movement of the member, said means including an element resting by gravity upon the blanks to hold them in contact with the bottom of the guideway. 95

18. In a machine of the class described, a guideway adapted to receive a plurality of can body blanks, means for feeding the blanks along the guideway to the pintle inserting mechanism and thereafter to the 100 feeding mechanism of a body forming machine; and means mounted on said body forming machine, to position the blank accurately on the feed mechanism of said machine. 105

19. In a machine of the class described, a guideway for receiving a plurality of can body blanks, means for feeding the blanks along the guideway to pintle inserting mechanism and thereafter to the feed mechanism 110 of a body forming machine; a positioning plate located above the feed mechanism of the body forming machine, and means for first shifting the plate to receive a blank and then for returning the plate to position the 115 blank accurately, and driving means for actuating both the blank feeding means and the positioning plate shifting means so as to operate both means in synchronism.

In testimony whereof I have hereunto set 120 my hand.

CHARLES V. STRICKLAND.
